DESIGN FOR A CLOTHES HANGER FOR AUTOMOBILE WINDOWS

Elmer J. Lauronen, Oakland, Calif.

Application May 14, 1941, Serial No. 100,940

Term of patent 14 years

To all whom it may concern:

Be it known that I, Elmer J. Lauronen, a citizen of the United States, residing in the city of Oakland, county of Alameda, State of California, have invented a new, original, and ornamental Design for a Clothes Hanger for Automobile Windows, of which the following is a specification, reference being had to the accompanying drawing forming part thereof.

Fig. 1 is a perspective view of a clothes hanger

for automobile windows, showing my new design.

Fig. 2 is a top plan view of the same.

Fig. 3 is a side elevational view.

Fig. 4 is a front elevational view of the design as the same would appear in position.

I claim:

The ornamental design for a clothes hanger for automobile windows, as shown.

ELMER J. LAURONEN.
